CLAIM

The ornamental design for a rehabilitation pad, as shown and described.

DESCRIPTION

FIG. 1 is a frontal isometric view of my new rehabilitation pad, showing the new design;

FIG. 2 is a frontal elevational view thereof;

FIG. 3 is a left side elevational view thereof;

FIG. 4 is a right side elevational view;

FIG. 5 is a top plan view thereof;

FIG. 6 is a bottom plan view; and,

FIG. 7 is a rear elevational view thereof.

The cross-hatching shown in all views is understood to represent fabric and would be continuous throughout the implied areas.
